US00D711107S

(12) **United States Design Patent**
Krotts(10) **Patent No.:** **US D711,107 S**
(45) **Date of Patent:** **** Aug. 19, 2014**(54) **COLLAPSIBLE STRUCTURE**338,892 A 3/1886 Walker
344,340 A 6/1886 Barrow
356,301 A 1/1887 Belknap(71) Applicant: **Bajer Design & Marketing, Inc.**,
Waukesha, WI (US)

(Continued)

(72) Inventor: **Dean B. Krotts**, Hartland, WI (US)

FOREIGN PATENT DOCUMENTS

(73) Assignee: **Bajer Design & Marketing, Inc.**,
Waukesha, WI (US)DE 281680 8/1913
DE 2015649 2/1971(***) Term: **14 Years**

(Continued)

(21) Appl. No.: **29/443,550**

OTHER PUBLICATIONS

(22) Filed: **Jan. 18, 2013**

"Magic Maaze" Frongate Mail-Order Catalog, Summer 1995, p. 32.

Related U.S. Application Data

(60) Division of application No. 29/432,608, filed on Sep. 18, 2012, now Pat. No. 680,329, and a continuation of application No. 29/425,054, filed on Jun. 19, 2012, now abandoned, which is a division of application No. 29/348,925, filed on Feb. 22, 2010, now Pat. No. Des. 661,900.

Primary Examiner — Kelley Donnelly(74) *Attorney, Agent, or Firm* — Ryan Kromholz & Manion, S.C.(51) **LOC (10) Cl.** ..... **03-01****CLAIM**(52) **U.S. Cl.**

The ornamental design for a collapsible structure, as shown and described.

(58) **Field of Classification Search****DESCRIPTION**USPC D32/35-37; D3/201, 301, 305, 307,
D3/314, 233, 246; D34/1; 232/43.4, 43.5,
232/43.2; 220/908-911

FIG. 1 is a perspective view of the embodiment;

See application file for complete search history.

FIG. 2 is a right side elevation view, the left side elevation view being identical;

(56) **References Cited**

FIG. 3 is a front elevation view, the rear elevation view being identical;

U.S. PATENT DOCUMENTS

FIG. 4 is a top plan view;

177,749 A 3/1876 Redden
216,227 A 6/1879 Sedgwick
217,362 A 7/1879 Gardner
218,277 A 8/1879 Kilham
251,325 A 12/1881 Walters
288,654 A 11/1883 Morse

FIG. 5 is a bottom plan view;

FIG. 6 is a perspective view of a second embodiment;

FIG. 7 is a right side elevation view, the left side elevation view being identical;

FIG. 8 is a front elevation view, the rear elevation view being identical;

FIG. 9 is a top plan view; and,

FIG. 10 is a bottom plan view.
